UNITED STATES PATENT OFFICE.

JACOB KRONHEIM AND ZOLTAN B. CSIKY, OF CLEVELAND, OHIO.

CONVERTIBLE SOFA CHAIR AND COUCH.

1,043,112.

Specification of Letters Patent.

Patented Nov. 5, 1912.

Application filed June 29, 1910. Serial No. 567,762.

To all whom it may concern:

Be it known that we, JACOB KRONHEIM and ZOLTAN B. CSIKY, subjects of Austria-Hungary, residing at Cleveland, in the county of Cuyahoga and State of Ohio, have invented certain new and useful Improvements in Convertible Sofa Chairs and Couches, of which the following is a specification.

10 Our invention relates to a convertible sofa chair and couch, the same being adapted to be used as a chair with or without a reclining back and as a base rocker and also to be opened into a couch or bed, all as herein-
15 after fully described and particularly pointed out in the claims.

In the accompanying drawings, Figure 1 is a vertical sectional elevation front to rear of our invention with the parts in the position of a chair but locked in respect to the base to prevent rocking. Fig. 2 is a cross section on a line corresponding substantially to $x-x$, Fig. 4, looking to the right. Fig. 3 is a plan view of a portion of the invention 25 showing the parts open to form a bed. Fig. 4 is a longitudinal sectional elevation of the structure partly broken out at one end and showing the position of the parts as they form a bed.

30 The invention herein is an improvement more particularly upon the construction of a combined chair and bed shown and described in an application filed December 31, 1909, Ser. No. 535,806. In the further development of said chair and bed a number of changes have been found to be necessary to render the structure altogether convenient and desirable and at least some of these are embodied in the present application. Thus, 35 the invention is comprised in three main portions or sections consisting of a middle section A, a back section B and a seat section C. These three sections are adapted to be folded together to constitute a chair as seen particularly in Fig. 1, and to be unfolded or opened in respect to each other to form a couch or bed, as seen in Fig. 4, or in plan, Fig. 3. Incident to this opening of the structure to constitute a couch or bed it 45 will be understood that the back B may be more or less inclined than shown in Fig. 1 to form what is known as a reclining chair, and in this connection it should be understood also that the entire structure rests upon a base or floor frame F upon which 50 the middle section A of the chair proper is

supported by rocker springs S, the idea of this particular part of the structure being that a spring rocking chair may be obtained in this way. However, when a reclining 60 chair is formed, or a bed or couch, it is not desirable to have the rocking action, and for this reason we provide braces to make the chair frame rigid with the base frame F. One of our improvements in this application consists in this mechanism.

In the above mentioned application there were hooks which connected the frames, but these had to be reached by hand whenever engaged or released and owing to the construction and relation of parts it was exceedingly inconvenient to reach these hooks as well as its being very objectionable to always have this to do to make so slight a change in the structure. Hence we have devised the present means which are convenient and effective and can be controlled from behind the chair by a small cord 2 when the spring action of the chair is to be restored but which will be automatically locked by a 70 spring 3 at the front when rigidity of the parts is desired. To these ends we employ front and rear swinging or pivoted brace rods suspended from the seat frame A and which have their extremities bent down at 75 right angles to form braces 4 and 5 respectively. The braces 4 at the front are shorter than the braces 5 at the rear, to accommodate the differences of distance between the two frames A and F at the front and rear 80 respectively, but otherwise they are the same in construction and operation. Links a connect said braces front and rear and have slots 6 in their rear ends supported on pins on the braces 5 and affording a certain 85 amount of play between the said front and rear braces to accommodate their operations. It will be noticed that the spring 3 is arranged in respect to braces 4 in such way as to exert a closing action thereon with a constant spring tendency and through links a 90 also pull the braces 5 to closing or rigid position. The cord 2 is connected with the braces 5 and adapted to pull against the spring to open position, and when the chair 95 is to be converted into a rocker the said cord is drawn far enough to withdraw the said braces and the extremity thereof is then engaged on the hook or catch 7 on the back of the chair. Then as the chair is to be made 100 rigid again it is only necessary to release the cord and the spring 3 will draw the parts to 110

bracing position and possibly a little rocking by hand will help braces 5 to come to position also under their spring pull b. It has been found desirable to have a slightly 5 ribbed rest plate 8 upon the frame F adapted to support the said brace legs and which are provided with a front flange to limit their forward movement to a vertical position, and the slot 6 in the links 5 affords 10 accommodation to the said braces as they take their position on the rests 8. In this way we are enabled to control the matter of rigidity and convert the structure into a rocking chair by merely handling the cord 2, the end of which is always convenient, 15 and the springs 3 and b close the braces.

Again, in the application above referred to we found that with a structure of this kind jointed here and there and depending 20 upon the opening or spreading of the end sections to get the desired tension to the mattress M the mattress was liable to sag and did not afford as comfortable a bed as it ought to. Hence we have improved the 25 structure by introducing a series of spring wires W transversely of the bed between the sides thereof and engaged with the top connecting bars 9 of the mattress supporting frame comprising the posts 10 with said 30 bars or links, and which is adapted to fold as before. When the bed is open or stretched the mattress M is sustained from edge to edge at its middle by these cross wires, which in a sense are incorporated therewith 35 and constitute a portion of the spring mechanism for carrying the bedding which comes upon the wire mattress. These transverse wires W run at an angle to each other from side to side of the bed and are supplemented 40 at the front by a series of spirally wound sustaining springs G which rest upon a cross piece g in the seat frame C. The said springs G and W coöperate with each other and afford all the additional spring 45 support at the middle of the bed which is required in addition to the spring action which the mattress M itself provides, and thus a very comfortable bed is made. The folded position of the several parts just 50 described comprising the mattress M and the said springs and the frame 9 is clearly seen in Fig. 1, where the said parts are entirely removed from observation and occupy space which otherwise would not be 55 occupied and where they are not in the way.

A third distinct and material improvement herein over the application above referred to is found in the means for making the back section B rigid with the middle 60 section A when the said back section is lowered more or less to or toward its lowest attainable position as when used for a bed. In the foregoing application a plain ratchet is shown as occupying the position relatively 65 of the ratchet 12 herein, but the said ratchet

is liable to become detached in its engagements and particularly when the tension of the mattress M is exerted to lift the back B from the lowered position seen in Fig. 4. This frequently occurred, and hence in the 70 present construction the ratchet 12 which engages on the cross portion 13 in the frame has locking notches n at its pivot end adapted to absolutely hold the head section in the desired position when down to form a bed. 75 For that matter all the notches of the ratchet could be made in the same way with recessed ends, or their equivalent, and such notches are required when the back is lowered to an approximately horizontal position 80 wherein it ought to be fixed rigidly with the remainder of the structure and particularly since said back should hold a given fixed position on account of the mattress M being connected therewith and dependent thereon to stretch the same to just the requisite tension. Otherwise the construction of the various parts herein and their operation is substantially the same in the application above mentioned and need 85 not be more particularly referred to. This applies to the folding end frame 14 for the mattress and braces 15.

What we claim is:

1. A convertible chair and bed, in combination with a mattress therein adapted to be stretched lengthwise and to be folded upon itself when out of use, and means to raise and support said mattress in use comprising a head section to which the mattress 100 is attached at one end, a foldable foot section and a pivoted support for the other end of the mattress in said foot section adapted to swing to an elevation clear of 105 said section, a middle section on which said foot section is adapted to be inverted and a pair of braces engaging the middle of said support and pivoted at the top and front of said middle section.

2. A convertible chair and bed having a 110 base section and a back section adapted to be lowered to approximately the same plane as said base section and a seat section adapted to be inverted at the front of the base, in combination with a spring wire 115 mattress attached at one end to said back section and a foldable frame pivotally mounted on the bottom of said seat section having the front end of said mattress attached thereto, and braces for said foldable 120 frame engaged with said base section, whereby the mattress is stretched when the bed is opened.

3. A convertible chair and bed comprising head and foot and middle sections respectively in hinged relations, in combination with a wire spring mattress adapted to be stretched lengthwise to form a bed and engaged at its head end with the upper end 125 of said head section, a foldable support for 130

the front end of said mattress mounted on said foot section and braces to hold the said support in raised position engaged at one end with said middle section and adapted to stretch the mattress automatically, and a double side support for the middle of the mattress foldably mounted on said middle section and having side connections at its top between its front and rear portions and

having the mattress attached to said support 10 and foldable therewith.

In testimony whereof we affix our signatures in presence of two witnesses.

JACOB KRONHEIM.
ZOLTAN B. CSIKY.
